(57) **CLAIM**

The ornamental design for a decal, as shown and described.

DESCRIPTION

FIG. 1 is a front view of a decal showing my new design, a rear view being a mirror image thereof;

FIG. 2 is a left side view of the decal, right side, top and bottom views being identical; and,

FIG. 3 is a top front side perspective view of the decal.

1 Claim, 3 Drawing Sheets

FIG. 1

FIG. 2

FIG. 3
